HANGER

Filed Jan. 30, 1948

For a description of the invention, reference is made to the drawings which form a part of this patent application.

UNITED STATES PATENT OFFICE

2,583,563

HANGER

Harry M. Habel, Oak Park, Ill.

Application January 30, 1948, Serial No. 5,309

1 Claim. (Cl. 211—89)

1. A clamp-type hanger including

This invention relates to hangers or racks for the support of such items as shoes and moreover, towels, hats and various other articles of clothing which frequently become displaced from their supported positions on vehicles such as airplanes, ships and trains.

The principal object of the present invention is to provide a clamp-type hanger wherein the clamp elements will firmly grip an article interposed therebetween.

Another object of the invention is to provide a clamp-type hanger which includes a pair of swingable clamp elements on different axes, which when brought together and under the weight influence of an article interposed therebetween will firmly grip the article and hold the same against accidental displacement.

A further object of the invention is to provide a hanger including a pair of clamp members which can be readily separated when an article is to be removed from supported position.

These and various other objects and advantages of the invention will become apparent to the reader of the following description.

In the drawings:

Figure 1 is a fragmentary front elevational view of the hanger.

Figure 2 is a vertical section and side elevational view of the hanger shown gripping a shoe, which is partly broken away.

Figure 3 is a fragmentary top plan view of the hanger.

Figure 4 is a fragmentary front elevational view showing a panel of hangers.

Referring to the drawings, numeral 5 denotes the inside of a door, or perhaps a wall, or a panel 6, as shown in Figure 4 attached to a door or wall 7.

If the hanger is used for shoes, the hangers are preferably arranged in pairs, as shown in Figure 4 and each hanger preferably includes a rectangular shaped frame 8 in which the clamp-like hanger, forming the present invention is mounted and which is generally referred to by numeral 9.

The frame 8 includes vertical side members 10, 10 and connecting upper and lower members 11, 11, the corners of the frame having openings for receiving nails or screws 12, driven into the supporting structure 5 or 6.

The clamp assembly includes an upper clamp jaw 13 and a lower clamp jaw 14, the upper clamp jaw 13 having a downwardly and outwardly curved tail portion 15, the lower por-

tion of which has an outwardly disposed and apertured ear 16 through which a pin 17 is disposed, this pin having its ends projected through openings 27 at the lower portions of cleats 18, 18, these cleats being nailed or otherwise secured to the side portions 10 of the frame 8. The lower end of the tail portion 15 has a downwardly projecting finger 19 against which an arm 20 depending from the jaw 14 engages, as shown in Figure 2, the jaw 14 having a rearwardly projecting ear 21, apertured to receive a supporting pin 22, which has its ends disposed into openings 28 in the upper portions of the cleats 18 and it is preferable that a coiled spring 23 be convoluted on the pin 22 toward one side of the jaw 14, with its upper end engaging the jaw 14, while its lower end abuts one of the cleats 18, to the end that the jaw 14 is urged downwardly, with the arm 20 pressing against the finger 19 to maintain the jaw 13 a rotated pulley in a clockwise direction, viewing the structure in Figure 2.

The opposed faces of the jaws 13, 14 have felt or cushioned face members 24, 25 to protect the article against which they engage.

To facilitate the lifting of the jaw 13 and separation of the jaws to remove or place an article, the jaw 13 has an upstanding finger engageable protuberance 29.

Figure 2 shows a shoe A with its back portion gripped between the jaws 13, 14.

It will here be observed that the jaws 13, 14 are on different axes and in rotating, the arcs described by the jaws 13, 14 have a differentiation or intersection of travel, with the purpose in view that these two jaws will lock together or against a supported article and assume the outwardly disposed position as shown in Figure 2, the arm 20 in pressing against the finger 19 having a tendency to rotate the jaw 13 on its axis 17 while the jaw 14 is itself rotating on an axis eccentric to that of the jaw 13, which will result in a camming action of the jaws and a locking effect between themselves incident to a clamping action against the article being supported.

This locking and clamping action can be broken, by simply pressing backwardly on the protuberance 29, to the end that the shoe or other article can be readily removed from between the jaws 13, 14.

It can be seen that such a hanger is definitely suitable for use on moving vehicles such as airplanes, ships, boats as well as automobiles.

While the foregoing description sets forth the

invention in specific terms, it is to be understood that numerous changes in the shape, size and materials may be resorted to without departing from the spirit and scope of the invention as claimed hereinafter.

Having described the invention, what is claimed as new is:

A hanger comprising a support, a pair of clamp elements, vertically spaced members on the support, upon which the clamp elements are pivoted, the lower clamp element having spring means connected to one of said members to cause downward movement of said element, the upper clamp element being provided with a leg, swingable on the other member carried by the support and provided with a finger, the lower clamp element being provided with a leg engaging the finger and adapted to rock the upper clamp element down-

wardly against the lower clamp element when a load is imposed upon the lower clamp element.

HARRY M. HABEL.
